[57] CLAIM

The ornamental design for a magnetic-mount kitchen article holder, as shown and described.

DESCRIPTION

FIG. 1 is a front elevational view of a magnetic-mount kitchen article holder showing my new design;
FIG. 2 is a right side elevational view thereof, the left side being a mirror image of that shown;
FIG. 3 is a top plan view thereof;
FIG. 4 is a bottom plan view thereof;
FIG. 5 is a rear elevational view thereof; and
FIG. 6 is a perspective view thereof.
